Westinghouse Electric & Manufacturing Com-
pany, East Pittsburgh, Pa., a corporation of
Pennsylvania

Application October 3, 1932, Serial No. 636,087

8 Claims. (CL. 62—4)

My invention relates to control apparatus, and particularly to control apparatus for effecting defrosting of the heat absorbing elements of mechanical refrigerators.

In mechanical refrigerators, especially of the domestic type, the accumulation of frost on the cooling unit has long been a problem because frost impairs the transfer of heat between the air within the refrigerator and the cooling unit. Furthermore, an excessive accumulation of frost on the evaporator may interfere with the removal of the ice trays located within the evaporator.

The usual way of accomplishing defrosting of the evaporator is to manually throw a switch to stop the operation of the refrigerating unit until the frost has melted off the evaporator. Automatic devices have also been provided for periodically interrupting the supply of current to the refrigerator so as to halt the operation of the refrigerating unit temporarily.

All of the foregoing schemes are objectionable in that the defrosting action may require considerable time, so much so that the frozen foods or ice in the evaporator are apt to be softened or melted and, furthermore, because the box temperature may be higher than is found desirable. In addition, the manually operated process is open to the objection that it requires considerable attention on the part of the user and to the objection that the user may forget to restart the mechanism, and as a consequence, spoil the food in the refrigerator box.

Other automatic and semi-automatic defrosting schemes have been provided wherein, for example, electric heaters are utilized to melt the frost on the evaporator but, all of such schemes entail such mechanical and electrical complication as to be undesirable.

With my invention, I effect defrosting of the evaporator by periodically permitting relatively hot refrigerant condensate as well as the refrigerant vapor discharged by the compressor of the refrigerator unit to enter the evaporator; the heat of the condensed refrigerant coupled with the amount of heat effected by the vapor circulated through the system, which vapor condenses in the evaporator, effects a very rapid melting of the frost on the evaporator, the time interval being so short that congealed food articles housed within the evaporator are not melted and the temperature of the food compartment chamber is not unduly raised.

At the outset of the defrosting cycle the circulated vapor obtains some of its heat from the

stored heat of the motor, compressor, condenser, etc., and during the remainder of the cycle the circulated vapor obtains heat due to the motor inefficiency and from the compressor friction.

It is an object of my invention, therefore, to provide an automatic or semi-automatic defrosting device for a mechanical refrigerator which shall be of less expensive construction and more reliable than the devices of this connection heretofore provided and which melts the frost on the evaporator with such rapidity as to avoid melting of the frozen food stuffs housed within the evaporator and to prevent undue rise in the food compartment temperature because of the defrosting feature.

These and other objects are effected by my invention as will be apparent from the following description and claims taken in connection with the accompanying drawing, forming a part of this application, in which:

Fig. 1 is a diagrammatic view of a refrigerating system containing one embodiment of my defrosting device;

Fig. 2 is a diagrammatic view of a portion of a refrigerating system such as shown in Fig. 1 and illustrates a second embodiment of my invention;

Fig. 3 is a diagrammatic showing of a refrigerating apparatus containing another embodiment of my invention; and,

Fig. 4 is a diagrammatic view of the timing mechanism shown in Figs. 1 and 2.

Although I have shown my invention as applied to a high side float controlled flooded compression system, it is obvious that my invention may be applied to any system having means for developing refrigerant vapor under pressure, a heat absorbing unit and areas in which the refrigerant per se is normally subject to a relatively high pressure, and other areas where it is normally subject to a relatively low pressure.

Referring now to Figs. 1 and 4 for a detailed description of the first embodiment of my invention, there is shown, diagrammatically, a conventional compression refrigeration system comprising a compressor 1 driven by a motor 2 and both preferably contained in a hermetically sealed casing 10. The compressor forces vaporous refrigerant at a relatively high pressure through a conduit 3 to a condenser 4 where the refrigerant is condensed with the assistance of air moved by a cooling fan 5. Condensed refrigerant flows through a conduit 6 to a float controlled valve 7. Through the valve 7, liquid refrigerant is normally delivered at a substantially uniform

rate and in a relatively small quantity, preferably to the bottom of an evaporator 8 through a conduit 9, wherein it is vaporized because of the low pressure maintained therein by the compressor 1, and the heat present in a cooling compartment 11 in which the evaporator is disposed. The vapor is then drawn back to the compressor through a conduit 12. The vaporization of refrigerant in the cooling unit 8 cools the food compartment 11. The operation of the compressor is intermittent and is controlled by a thermostat 13 which operates contact means 14 in supply line 15, the action of the thermostat 13 being responsive to cooling unit temperatures in a manner 15 well understood in the art.

For the sake of clearness, the condenser 4 and conduits 3 and 6 are hereinafter referred to as the "high side" of the system since a normally high pressure obtains therein, while the evaporator or heat absorbing unit 8 and conduits 9 and 12 are termed the "low side" of the system since normally a relatively low pressure obtains therein. The compressor 1 and the float valve 7 define the high and low pressure portions of the 25 system.

In order to remove frost from the cooling unit 8 and to prevent substantial accumulation of frost, the float controlled valve 7 is constructed in the following manner. A main casing 16 of 30 any suitable material is provided, and a non-magnetic cap 17 is disposed preferably on the top of the casing 16. A float ball 18 is contained in the casing 16 and is connected through suitable links and levers to the valve 7, which has a seat 35 19, in such a manner that when the float 18 rises due to accumulation of liquid refrigerant in the casing 16, the valve 7 is opened and allows liquid refrigerant to flow to the cooling unit 8. Attached to the upper portion of the float 18 is a 40 magnetic plunger 21 which extends partly into the non-magnetic cap 17.

A coil 22 is disposed around the cap 17 in such a manner that, when the coil is energized, the plunger 21 is pulled upwardly thus raising the 45 float 18, opening the valve 7, and placing the high and low sides of the system in unrestricted communication with each other.

In order to accomplish automatic defrosting rapidly, the coil is connected through leads 23 to 50 a switching and timing device 24, as fully illustrated in Fig. 4. The switching and timing device 24 is set to energize the coil 22 at predetermined times, at which times the valve 7 is opened and warm liquid refrigerant flows from the float 55 casing 16 and the condenser 4. As is herein-after described, the valve 7 is kept open for a sufficient length of time to allow the condenser pressure to drop considerably, whereupon, if the compressor 1 is running, vaporous refrigerant pumped 60 by the compressor will not be condensed but will be forced in the vapor state directly to the cooling unit 8, preferably entering the bottom thereof to ensure complete circulation of the non-condensed refrigerant. Because of the low temperature of the cooling unit 8 and the refrigerator cabinet 11 and also due to the increased pressure in the cooling unit 8 the refrigerant is at least 65 partially condensed in the cooling unit thus giving up its latent heat of condensation to the cooling unit and also its sensible heat which has been obtained from the motor 2 and compressor 1. Since the same amount of refrigerant is evaporated in the cooling unit as is condensed therein, the latent heats of evaporation and condensation balance so that the heat actually given 75

up to the cooling unit is the sensible heat contained in the non-condensed refrigerant vapor which is delivered thereto. At the beginning of the defrosting cycle substantially all of the non-condensed vapor delivered to the cooling unit 8 is 5 condensed therein. However, as the temperature of the cooling unit rises some of the vapor does not condense in the cooling unit 8 but, since it enters at the bottom of the cooling unit 8, bubbles through the liquid contained therein 10 neither condensing nor evaporating and the vapor is thereafter drawn directly back to the compressor 1. However, most of the sensible heat of the vapor which bubbles through the liquid in the cooling unit 8 is given up to the cooling unit. 15 The cooling unit 8 is therefore heated rapidly and frost is quickly melted. After a predetermined time the coil 22 is deenergized by the timing and switching device 24 whereupon the refrigerating apparatus is returned to its normal 20 operation with the restricted connections 7, 19 dividing the system into high and low sides.

It will be noted that, if the compressor 1 is not operating when the coil 22 is energized, as soon as warm liquid refrigerant from the condenser 4 25 flows to the cooling unit 8, the thermostatic control 13 will operate to close contacts 14 and start the motor 2 which drives the compressor 1. Positive delivery of non-condensed refrigerant to the cooling unit 8 is therefore assured. As shown in 30 Fig. 1, the thermostatic element is generally, although not necessarily, placed in metallic contact with the evaporator 8.

Before explaining the specific operation of the timing and switching device 24, it is well to explain that the amount of frost accumulating on the cooling units of mechanical refrigerators in a given time depends largely on the humidity of the ambient atmosphere, the amount of moisture contained in the articles placed in the refrigerator cabinet, the temperature of the cooling unit and the amount of air circulation in the food compartment and over the cooling unit. Since all these factors are variable with the refrigerator, the location and the user, it is obvious 45 that for the most advantageous operation of my device at predetermined intervals, it must be adjustable as to the length of the defrosting period and/or their frequency.

The timing device, on the other hand, must 50 maintain the connection between the high and low sides of the system in an unrestricted condition for a long enough time to allow non-condensed refrigerant to be forced to the low side, and therefore a predetermined minimum setting 55 must be provided which varies with each type and size of refrigerator.

The timing device is therefore equipped with a minimum setting, preferably arranged at the factory, and an adjustable upper time limit device which may be adjusted by the user. Since the defrosting cycle slightly increases the overall current consumption, it is preferable to have the timing device set to initiate defrosting not more than once every twenty-four hours, and the upper time limit setting will, of course, vary with the frequency of defrosting.

Turning now to a detailed description of my timing and switching device 24, numeral 25 designates small clock motor of conventional design, the movement of which is reduced through a gear chain 26 and which finally rotates a wheel 27. A radial slot 28 is cut out of the wheel 27 and a projection member 29 slides in the slot. A small screw 30 is provided on the member 29 75

to hold it in the position desired in the slot 28. Disposed adjacent to the wheel 27 is a bell-crank lever 31 disposed movably on a trunnion 32 and extending in two directions therefrom. A contact 33 is disposed on an end 31a of the bell-crank lever 31 and a second contact 34 is adapted to be engaged by the first contact 33. A helical spring 35 and a stop 36 maintain the lever 31 in its operating position. The contacts 33 and 34 are connected to a coil (not shown) by leads 40 positioned as shown in Figs. 1 and 2 which, when energized, starts the defrosting period and when deenergized stops the defrosting period.

The operation of the device is as follows: The projecting member 29 is rotated by the clock device 25 and once in every revolution, which is preferably not more than once a day, it contacts with end 31b of the bell-crank lever 31, thus turning the lever about the trunnion 32, overcoming the force of the helical spring 35 and closing the contacts 33 and 34. The projection 29 maintains its engagement with the lever 31 for a period of time above a certain minimum which is determined by the distance of the inner end 25 of the slot 28 from the center of the wheel 27, the projection 29 being set in the slot 28. When the projection 29 is at its innermost position, the contacts are closed for the least period of time; as the projection 29 is moved outwardly in the slot 28, the period of time the contacts 33 and 34 engage increases since the projection 29 engages the end 31b of the lever 31 for a longer time.

It is apparent that, by sliding the adjustable projection 29 in the slot 28, the time between closing and opening the contacts 33 and 34 and energizing and deenergizing the coil (not shown) may be varied within certain limits, whereby more or less non-condensed refrigerant is delivered to the cooling unit 8 through a non-restricted connection between it and the compressor 1, whereby the frost on the cooling unit may be completely melted and the system may start in normal operation as soon as the frost is all melted.

In the second embodiment of my invention, illustrated in Fig. 2 of the drawing, a float controlled valve 41 contained in a casing 42, is connected into the refrigerating system in the same manner as shown in Fig. 1, and operates as an ordinary high side float in a manner well known in the art. A conduit 43 connects the bottom of the float valve casing 42 and a discharge conduit 44 therefrom, and is provided with a valve 45 and a co-operating valve seat 46 therefor contained in a casing 47. The valve casing 47 has a non-magnetic tube 48 connected at its upper end. The conduit 43 is arranged to by-pass the float controlled valve 41 when the valve 45 is opened, whereby refrigerant flows unrestrictedly from the compressor to the cooling unit. As explained with respect to Fig. 1, the valve 45 is maintained in an open position by a timing and switching device 49 long enough to allow the compressor to force non-condensed refrigerant to the cooling unit, thereby rapidly heating the cooling unit and melting the frost thereon.

In order to open the by-pass valve 45, a magnetic plunger 51 is attached to the by-pass valve 45 and is disposed within the non-magnetic tube 48. A coil 52 is disposed outside the magnetic tube and is energized at and for predetermined intervals by the timing and switch device 49 which is preferably the counterpart of that shown in Fig. 4. When the coil 52 is energized, the plunger 51 is pulled upwardly, thus opening the by-pass

valve 45 and allowing liquid and then non-condensed refrigerant to flow unrestrictedly from the compressor to the cooling unit, the non-condensed refrigerant condensing therein and rapidly heating the cooling unit to melt the frost therefrom. 5

In Fig. 3, I have illustrated another embodiment of my invention which is semi-automatic in operation. In other words, the defrosting cycle of the refrigerator must be initiated manually, but the refrigerator is returned to normal operation 10 automatically. It will be obvious that in this embodiment of my invention, an electric device may be used for automatically initiating the defrosting cycle if desired. It will also be obvious that the control system shown may be applied 15 directly to a float valve as shown or it may be applied to a by-passing arrangement as shown in Fig. 2.

In this embodiment of my invention, a motor 56 energized through leads 57 drives a compressor 58, both the motor and compressor being preferably contained in a hermetically sealed casing 50, and pumps vaporous refrigerant to a condenser 59 which is cooled by a fan 60. From the condenser, liquid refrigerant flows into a float valve 25 casing 61 and as the level therein rises, a float 62 is raised and a valve 63 is opened, allowing small quantities of refrigerant to flow at a substantially uniform rate to a cooling unit 64 where the liquid evaporates and absorbs heat from a food chamber 65 before it is drawn back to the compressor 58. The motor 56 is operated in response to evaporator temperature and is controlled by a thermostatic device 66 and a switch 67 in the motor electrical line 57 in a manner well known in 35 the art, the compressor 58 therefore operating intermittently.

In order to accomplish defrosting, it is desired again to allow hot liquid and non-condensed refrigerant to flow unrestrictedly from the compressor 58 to the cooling unit 64. This is accomplished by providing the float casing 61 with a sylphon bellows 68 therein, and so disposing the bellows that expansion thereof will open the valve 63 and allow refrigerant liquid and vapor to pass 45 unrestrictedly therethrough.

In order to effect opening and closing of the valve, the bellows 68 is connected through a conduit 69 to a gas filled bulb 71 disposed outside the float casing 61 and which is surrounded by 50 a heater coil 72. When heat is applied to the bulb 71 by the coil 72, the gas in the bulb expands, thus expanding the bellows 68 and opening the valve 63. It is necessary to provide means for energizing the heating coil 72 and for maintaining the valve 63 open for a sufficient time to ensure that non-condensed refrigerant will be delivered directly from the compressor 58 to the cooling unit 64 and condense therein. This means comprises a push button 73 which is maintained 60 normally in the position shown by a spring 74, a set of contacts 75 which are closed by pushing the button 73 inwardly to energize the electric heater 72 and a thermostatic latch comprising a hook 76 on the end of the push button 73 and a 65 bimetal strip 77 which is placed adjacent to the heater coil.

When the push button 73 is operated, the heater 72 is energized by the closing of the contacts 75, the bimetal strip 77 holding the hook 76 and maintaining the contacts 75 closed. The strip 77 bends after a predetermined time due to the heat emanating from the coil 72, and releases the hook 76, whereupon the spring 74 opens the contacts 75. As the gas in the bulb contracts thereafter, 75

the bellows 68 also contracts and returns the float controlled valve 63 to its normal operation in the refrigerating cycle.

From the foregoing, it will be apparent that I have illustrated several embodiments of my invention for rapidly defrosting the cooling unit of a mechanical refrigerator at times predetermined either manually or automatically, which systems are based on the broad idea of temporarily using the cooling or vaporizing unit as a condenser, whereby the sensible heat of the refrigerant is transferred rapidly to the evaporator. By this means, frost is melted quickly off the cooling unit without melting ice or frozen desserts, and without allowing the refrigerator box temperature to rise to a point where spoilage is likely to occur. I have also provided a variable or adjustable defrosting device to meet various conditions, the adjustments being determined by the user of the device.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

30 What I claim is:

1. In a refrigerating system, the combination of a heat absorbing element normally subject to accumulation of frost thereon, a compressor for circulating refrigerant vapor, a condenser for normally supplying the refrigerant after condensation to the heat absorbing element to vaporize therein and cool the same, means for periodically supplying non-condensed refrigerant to the heat absorbing element and means for maintaining the compressor in operation for the time that non-condensed refrigerant is supplied to the heat absorbing element, whereby the heat of the vapor is absorbed by said heat absorbing element to rapidly defrost the same.

45 2. In a refrigerating system, the combination of an evaporator normally subject to the accumulation of frost thereon, a compressor for circulating refrigerant vapor, a motor for driving the compressor, a sealed casing for surrounding both the motor and compressor and containing refrigerant in heat conducting relation therewith, a condenser for normally liquefying the compressed refrigerant vapor, means for normally supplying the refrigerant vapor after condensation to the evaporator to vaporize therein and cool the same, and means for periodically supplying non-condensed refrigerant vapor containing sensible heat of the motor, compressor and compression to the evaporator, whereby the non-condensed vapor is condensed therein and the heat of condensation and the sensible heat of the vapor is absorbed by the evaporator to rapidly defrost the same.

60 3. In a refrigerating system, the combination of an evaporator normally subject to the accumulation of frost thereon, a compressor for circulating refrigerant vapor, a motor for driving the compressor, a sealed casing for surrounding both the motor and compressor and containing refrigerant in heat conducting relation with the motor and compressor, a condenser for normally liquefying the compressed refrigerant vapor, means for normally supplying the condensed refrigerant to the evaporator to vaporize therein and cool the same, and means for periodically

supplying non-condensed refrigerant vapor, containing sensible heat absorbed from the motor and compressor and the heat of compression to the evaporator, whereby the non-condensed vapor is condensed therein and the heat of condensation and the sensible heat of the vapor are absorbed by the evaporator to rapidly defrost the same, and means for maintaining the compressor in operation while non-condensed refrigerant is being supplied to the evaporator.

10 4. In a refrigerating system, the combination of an evaporator normally subject to the accumulation of frost thereon, a compressor for circulating refrigerant vapor, a condenser for normally liquefying the compressed refrigerant vapor, means including a valved conduit for normally supplying condensed refrigerant to the evaporator to vaporize therein and cool the same, means providing a by-pass around the valved conduit, means for periodically directing non-condensed refrigerant vapor from the compressor to the evaporator through said by-pass, whereby the heat of the vapor is absorbed by said heat absorbing element to rapidly defrost the same and means for maintaining the compressor in operation while the last-mentioned means is inactive.

25 5. In a refrigerating system, the combination of a heat absorbing element normally subject to the accumulation of frost thereon, a compressor for supplying compressed refrigerant vapor, a condenser for liquefying the compressed refrigerant vapor, means including a normally restricted connection for supplying the refrigerant after condensation to the heat absorbing element for vaporization therein to cool the same, and means for periodically supplying noncondensed refrigerant vapor from the compressor to the heat absorbing element to heat the same, said last means comprising a heater energized by manual means, a thermostatic latch adapted to be operated by heat, a thermostatic bulb adjacent to the heater and said valve, said thermostatic bulb when heated by said heater adapted to provide a nonrestricted connection between the compressor and heat absorbing element, said thermostatic latch when heated adapted to return said connection to its normally restricted state a predetermined time after the action of the thermostatic bulb has opened the valve.

30 6. The method of rapidly defrosting the evaporator of a mechanical refrigerator in which a relatively high temperature refrigerant vapor is circulated in heat exchanging relation with and by a hermetically sealed motor-compressor unit to a condenser for normally liquefying the refrigerant vapor in the condenser and wherein the condensed vapor is, in turn, normally supplied in a restricted manner to an evaporator to vaporize therein and cool the same, which consists in discharging first condensed refrigerant liquid and then uncondensed refrigerant vapor which both contain motor and compressor heat into the evaporator in an unrestricted manner while the compressor is running and at the same time removing refrigerant vapor from the evaporator, whereby the evaporator first absorbs sensible heat from the condensed refrigerant which partially balances the heat dissipated by the continuous vaporization of the refrigerant, secondly absorbs both the heat of condensation and the sensible heat of the non-condensed refrigerant vapor which is supplied to the evaporator and is condensed therein, which heat of condensation alone balances the heat dissipated by the continuous vaporization of refrigerant and thirdly ab-

10 7. In a refrigerating system, the combination of a unit for normally absorbing heat, means for periodically adding a predetermined minimum amount of heat to the unit, means for thereafter suddenly adding more heat to the unit at a substantially faster rate than the rate at which the minimum amount of heat is added, means for varying the total amount of heat added at the faster rate and means for rendering the heat add-

ing means ineffective after predetermined amounts of heat have been added to the unit.

8. The method of rapidly defrosting an evaporator of a refrigerating system in which, normally, a compressor discharges compressed refrigerant vapor at a relatively high pressure to a condenser for liquefaction therein and wherein condensed refrigerant vapor is supplied through a restriction to the evaporator maintained at a relatively low pressure by the compressor for effecting vaporization of the liquid refrigerant therein, which consists in, first, circulating condensed refrigerant fluid to the frosted evaporator without restriction, secondly, circulating refrigerant vapor to the frosted evaporator without restriction, and maintaining the circulation of refrigerant vapor during the defrosting period by operation of the compressor.

MATSON C. TERRY.
